UNITED STATES PATENT OFFICE.

MAX WILLESTYN, OF NEW YORK, N. Y.

MACHINE FOR CLEANING CRUDE FUEL-OIL.

1,150,086.

Specification of Letters Patent. Patented Aug. 17, 1915.

Application filed February 25, 1914. Serial No. 820,653.

To all whom it may concern:

Be it known that I, MAX WILLESTYN, a subject of the Queen of Holland, residing at New York, borough of Brooklyn, has invented certain new and useful Improvements in Machines for Cleaning Crude Fuel-Oil, of which the following is a specification.

My invention relates to improvements in machines for cleaning crude oil of its dirt, and refuse before being passed through the burners for ignition, and the objects are, first in combining two machines into one, thereby reducing space and obtaining a continuous flow of clean oil; second, in forming a chamber in the exterior casing in close proximity to a movable strainer, so that a pressure blast can pass through only a small portion of the periphery of the strainer while being moved past the contained pressure chamber; third in so forming a deflecting plate or brush, within the strainer, and opposite the contained pressure chamber in the casing, so that the movable strainer passes through the opening formed by these two parts, whereby the pressure can be deflected through and circumferentially on the interior surface of the strainer, thereby cleaning and cutting loose all refuse material; fourth, causing the strainer to be partially, or wholly rotated on its axes, in one or both directions thereby assisting the deflecting brush in cleaning the strainer; and fifth, in so arranging the casing with its contained chambers, with regard to the strainer, that all parts can be cleaned without being taken apart.

I attain the objects of my invention by illustrations shown in the accompanying drawings, in which—

Figure 1 is a vertical elevation, of the entire machine partly in section. Fig. 2 is a plan view of the machine, in part section on line II—II of Fig. 1. Fig. 3 is a side elevation of the interior deflecting brush partly in full and partly in section. Fig. 4 is a broken front elevation of the deflecting brush enlarged.

Similar letters refer to similar parts throughout the several views.

The confining cylinders 10 and 11, connecting plates 12 and 13, with lugs 14, 15, 16 and 17 constitute the frame work of the machine.

Attached to the top of the cylinders 10 and 11 are caps 18 and 19 recessed into the

cylinder as at 20 and secured by stud bolts 21, and nuts 22.

Centrally located in each cap there is formed a stuffing box 23 with a gland 24, 60 held and adjusted in position by stud bolts 25 and nuts 26.

Passing through gland 24, stuffing box 23, and bearing 26^a in the bottom of the cap is a stem 27, having one end squared as at 28, 65 the other end being enlarged as at 29, and secured to the perforated strainer, by any suitable means, preferably by screws 30.

Extending downwardly from the underside of the head 29 and concentric with its center, is a centering teat 31.

To the head 29 is secured the cylindrical strainer 32 which is of smaller diameter than the inner diameter of the confining cylinder, the said strainer is perforated 75 through and over its entire surface by openings 33, except where it rests in its bearings at the top, and bottom of the cylinder. The perforations in these strainers are preferably made smaller than the openings in the burner so that any matter which passes through the strainer will also pass through the burner without clogging.

The cylindrical strainer 32, as shown in Fig. 2, is set off the center of its confining cylinder 10, (although not absolutely necessary) so that a portion of its periphery bears against the walls of the chamber 34, which extends beyond the interior wall of the confining cylinder, and forms a port 90 opening for the pressure blast, preferably steam, to act direct against the strainer; and a clean oil chamber 34^a to convey the clean oil to its outlet.

By the arrangement shown, the strainer 95 can be rotated in its bearing at the top and bottom of the cylinder, to the right or left a full revolution or more if desired by means of the squared stem.

On the bottom of the casing is formed a 100 boss 35 which extends upwardly and within the bottom of the casing to a point 36, and within the boss is formed the inlet passage 37 for the oil.

Centrally within the boss, is secured in 105 any suitable manner a tubular column 38 with perforations 39, and extending upwardly to the underside of the head 29, where it is centered upon the teat 31.

Surrounding the tube 38 at the top and 110 bottom are arms 40 and 41 having openings 42 and 43. Connecting these arms is a plate

or deflecting brush 44, which bears against the inner surface of the cylindrical strainer which is of sufficient width and length to cover the port opening of the confined pressure chamber 34, and is kept from turning upon the pipe 38 by a key or lug 45.

The brush on the side adjacent to the strainer is recessed as at 46, to cover the entire depth of the perforations in the strainer. On either side of this recess are bearing faces 47 and 48. One, or both of these faces 47 or 48 may be recessed or grooved as at 49 in order that the strainer may accomplish its work when turned in either direction, but I prefer to recess but one face as shown, such recesses being formed at an angle to the horizontal plane for directing the pressure blast downwardly and circumferentially against the inner surface of the strainer. Refuse from the surface of the strainer can escape from recess 46 by a passage 50 which connects with the incline discharge passage 51 below the strainer, and into which all refuse is discharged.

In describing the operation of the machine each cylinder being a duplicate, it is necessary to follow the course of the oil, and refuse through one cylinder only to fully understand its working. Therefore referring to the sectional portion of Figs. 1 and 2, the highly heated fuel oil under pressure passes up through the inlet valve 52 to pipe 38, (valve 56 being closed) then through the perforations 39 to the interior of the strainer 32, where particles of solid asphalt, sand, and other refuse, are screened against the strainer on the interior surface. While the collecting of refuse is going on, the clean oil is passing through the strainer, into chamber 34^a, then by the outlet 53, (see Fig. 2,) to the piping 54, and valve 55 to the burner for ignition. This goes on until the flow of oil is not sufficient to supply the burner. When it then becomes necessary to clean the strainer in the first cylinder and use the second cylinder for keeping up a new supply of clean oil for fuel. In making this change the inlet valve 56 is opened to the cylinder 11 and the outlet valve 55 shut off from cylinder 10 and opened to cylinder 11 thus continuing the flow of clean oil under pressure to the burner. The inlet valve 52 is then closed, after which the refuse discharge valve 57 to the cylinder 10 is opened as well as the steam inlet valve 58. With the introduction of the pressure blast, it forces all material accumulated in the perforations 33 to the recess 46 in the brush 44, part of which refuse is carried downward and outward through the passage 50 into the discharge refuse chamber 51, the balance being carried by the speed of the blast through the openings 49 on the face of the deflecting brush in a circumferential and

downward direction against the inner surface of the strainer. The cleaning process is assisted by turning the stem 27 and strainer 32, by suitable means applied to the squared end of the spindle 27. As a rule two revolutions of the strainer are sufficient to thoroughly clean all refuse from the strainer which is carried downwardly to the inclined discharge passage 51 and outward through valve 57.

The cleaning of the cylinder 10 having been accomplished, all valves are closed to this cylinder, and opened only when desired to use the cylinder in its routine order. In using these cylinders an expert operator can keep the supply of oil to the burner by the use of one cylinder only, as it takes scarcely one half a minute to clean the screen thoroughly, and when the supply of oil is shut off for the purpose of cleaning, there remains enough oil in the air vessel under pressure between the cleaner, and burner, to last during the process of cleaning, without any appreciable effect upon the fire. In this case the second cylinder is simply held in reserve in case of accident or to give the first cylinder a rest for inspection.

I am aware that strainers have been used for cleaning crude fuel oil, also a blast directed at the strainer for cleaning the strainer of refuse, and also where the strainer has been cleaned without taking the work apart, I do not wish to confine myself to the exact construction shown, as changes can be made without departing from the spirit of my invention.

Having thus described my invention, I claim as new and desire to secure by Letters Patent:—

1. A machine for separating dirt, and refuse from crude fuel oil, consisting of a confining cylinder with inlet and outlet port for oil, a pressure blast port, and a refuse outlet, all openings being under control, a cylindrical strainer bearing upon the wall of a blast port within the confining cylinder, and means for rotating the strainer in either direction upon its axis past the blast port opening.

2. A machine for separating dirt, and refuse from crude fuel oil, consisting of duplicate confining cylinders, either of which can be used continuously, while the duplicate cylinder is held in reserve, each confining cylinder being provided with inlet and outlet port for oil, a pressure blast port, and a refuse outlet, all openings being under control, a cylindrical strainer within its corresponding confining cylinder, open at one end to the refuse outlet while bearing upon the wall forming a port for a pressure blast, and means for rotating the strainer at will in either direction past the blast port opening.

3. A machine for separating dirt, and

- refuse from crude fuel oil, consisting of duplicate confining cylinders, adapted to be used alternately, each cylinder being provided with inlet and outlet port for oil, a pressure blast port, and an outlet for refuse, 5 all openings being under control, a rotatable cylindrical strainer for each corresponding confining cylinder, open at one end to the outlet for refuse, while bearing upon the wall of a pressure blast port within the confining cylinder, whereby a blast when desired, may be directed against, and through the strainer to remove the refuse adhering thereto.
- 10 4. A machine for separating dirt, and refuse from crude fuel oil, consisting of duplicate confining cylinders, adapted to be used alternately, each cylinder being provided with ports for oil, a pressure blast port, and refuse outlet, all openings being under suitable control, a cylindrical strainer for each corresponding confining cylinder, closed at one end, and open at the opposite to the outlet for refuse, the said strainer being placed tangentially against the inner 20 wall of its confining cylinder, and over the pressure blast port, and means for rotating the strainer in either direction at will.
- 25 5. A machine for separating dirt, and refuse from crude fuel oil, consisting of duplicate confining cylinders, adapted to be used alternately, each cylinder being provided with an inlet port for oil located in the passage way for refuse, an outlet port for oil, and a pressure blast port, each of the openings being under the control of valves, a cylindrical strainer for each corresponding confining cylinder the said strainer being located within its confining cylinder, and in 30 contact with the wall of a pressure blast port, means for rotating the strainer in either direction, a perforated pipe within the strainer for distributing the oil equally to all parts, and connected to the inlet opening for oil.
- 35 6. A machine for separating dirt, and refuse from crude fuel oil, consisting of duplicate confining cylinders, each provided with its inlet and outlet port for oil, a pressure blast port, and a refuse outlet, a cylindrical strainer for each corresponding confining cylinder, a delivery pipe within the strainer supporting a stationary deflecting brush, said brush bearing upon the inner surface 40 of the strainer, and located over the blast port in the wall of the confining cylinder, whereby a pressure blast when forced through the strainer is deflected by the brush upon the inner surface of the strainer.
- 45 7. A machine for separating dirt, and refuse from crude fuel oil, consisting of duplicate confining cylinders, each cylinder being provided with inlet and outlet port for oil, a pressure blast port, and refuse outlet, all 50 openings being under control, a cylindrical strainer for each confining cylinder, a perforated pipe within the strainer, a deflecting brush supported upon the pipe, and bearing upon the inner surface of the strainer, and over a pressure blast port in the confining cylinder, said deflecting brush having a recessed chamber upon its bearing face, with grooves leading therefrom for directing a pressure blast circumferentially upon the inner surface of the strainer.
- 55 8. A machine for separating dirt, and refuse from crude fuel oil, consisting of duplicate confining cylinders, each provided with ports for oil, a pressure blast port, and refuse outlet, a cylindrical strainer for each corresponding confining cylinder, a perforated pipe within the strainer, a deflecting brush supported by the perforated pipe, and over a blast port within the confining cylinder, said brush having a chambered face, with a passage leading from one end of the chamber to the refuse outlet, grooves in the wall forming the chamber, set at an angle to a horizontal plane, whereby a blast can be directed circumferentially and downwardly 60 against the inner surface of the strainer to assist in removing the refuse.
- 65 9. A machine for separating dirt, and refuse from crude fuel oil, consisting of duplicate confining cylinders, each provided with inlet, and outlet port for oil, a pressure blast port, and refuse outlet, a cylindrical strainer for each corresponding confining cylinder, a perforated pipe within the strainer, a stationary deflecting brush supported by the perforated pipe, said brush having a chambered face, grooves leading from the chamber, and means for securing the deflecting brush over the pressure blast port of the confining cylinder.
- 70 10. A machine for separating dirt, and refuse from crude fuel oil, consisting of duplicate confining cylinders, with their several ports controlled by valves, a cylindrical strainer of smaller diameter than the cylinder in which it is confined, located over and bearing upon the walls of a pressure blast port, a chamber formed between the outer wall of the strainer and inner wall of the confining cylinder except at the point of 75 contact with the wall of the pressure blast port, said chamber being adapted to receive the oil from which the dirt, and refuse has been removed.
- 80 11. A machine for separating dirt, and refuse from crude fuel oil, consisting of duplicate confining cylinders, each being provided with a stuffing box at one end, and an inclined refuse outlet at the opposite, inlet port for oil, a pressure blast port, and an outlet port for oil, all openings being under control of valves, a cylindrical strainer for each corresponding confining cylinder, adapted to be rotated at will from the exterior in either direction, the said strainer 85

being open at one end to the refuse outlet, a delivery pipe for oil, within the strainer, a stationary deflecting brush bearing upon the inner surface of the strainer and located over a pressure blast port of its confining cylinder.

In testimony whereof, said MAX WILLEMSTYN, has signed his name to this specifica-

tion in the presence of two subscribing witnesses, this twenty-fourth day of February, 1914.

MAX WILLEMSTYN.
